UNITED STATES PATENT OFFICE.

CHARLES SIWITZKY, OF NEW YORK, N. Y.

DESIGN FOR A REFRIGERATING-CASE.

SPECIFICATION forming part of Design No. 25,068, dated January 21, 1896.

Application filed October 23, 1895. Serial No. 566,666. Term of patent 7 years.

To all whom it may concern:

Be it known that I, CHARLES SIWITZKY, a subject of the Emperor of Russia, and a resident of New York, county and State of New York, have invented and produced a new, useful, and original Design for a Refrigerating Show-Case, of which the following is a specification, reference being had to the accompanying drawing, constituting part thereof.

10 The figure is a perspective view of a refrigerating show-case made after my design. My design represents a rectangular show-case set on a base artfully molded and wider than the body of the show-case, an ornamental top and an ornamental receptacle for ice.

15 The design shows the case composed of slender circular columns *a* smoothly finished and serving as frames for glass plates forming the walls of the show-case. The design for the 20 molding around the base of the case, connecting the body with the base, shows a convex surface to conform with the design of the base. The front side of the case is divided into five panels, the second and fourth of 25 which are filled with rectangular doors composed of framing similar in style and design to the body of the case.

The side opposite the front side is divided into three panels, and the middle panel is 30 filled with a door of similar design as the

doors in the front side. The other two sides are plain panels.

The upper edge of the body of the case is surmounted by a projecting convex molding *d* carrying a castellated border *f* supported on 35 cornice *e* composed of a reverted console.

The top of the case represents a low pyramid rising from a socket, designed in Byzantine style. This socket is formed of a rectangular base-plate *p*², having its upper edge 40 rounded into a concave curve. Within the receded upper edge of this base-plate another plate *p'* is represented with its upper edge convexly molded, and concentrically upon this plate rests pyramid *p*.

The design of the base of the case is a symmetrical reverse of the cornice. Its dimensions are, however, as apparent from the drawing, appropriately larger.

I claim—

50 The design for a refrigerating show case as shown and described.

In witness that I claim the design described in the foregoing specification I have signed my name in the presence of two subscribing 55 witnesses.

CHARLES SIWITZKY.
